TABLE RADIO OR SIMILAR ARTICLE

Akira Katoh, Tokyo, Japan, assignor to
General Electric Company

Filed May 28, 1971, Ser. No. 148,292

Term of patent 14 years

Int. Cl. D14—03

U.S. Cl. D56—4 B

FIG.4

FIG.5

FIG.6

FIG. 1 is a front elevational view of a table radio or similar article, showing my new design;

FIG. 2 is a left side elevational view;

FIG. 3 is a right side elevational view;

FIG. 4 is a rear elevational view;

FIG. 5 is a top plan view; and

FIG. 6 is a fragmentary bottom plan view thereof.

Portions of the drawing figures are diagonally lined to indicate transparency, structure which would be visible through the transparent surface being omitted for convenience in illustration.

I claim:

The ornamental design for a table radio or similar article, as shown and described.
